UNITED STATES PATENT OFFICE.

RAYMOND A. HEISING, OF EAST ORANGE, NEW JERSEY, ASSIGNOR TO WESTERN ELECTRIC COMPANY INCORPORATED, OF NEW YORK, N. Y., A CORPORATION OF NEW YORK.

SYSTEM OF COMMUNICATION.

Application filed September 23, 1919. Serial No. 325,729.

To all whom it may concern:

Be it known that I, RAYMOND A. HEISING, a citizen of the United States, residing at East Orange, in the county of Essex, State 5 of New Jersey, have invented certain new and useful Improvements in Systems of Communication, of which the following is a full, clear, concise, and exact description.

The present invention relates to the transmission of intelligence, particularly over long distances, and a part of the way at least by radiated waves. It has for an object the attainment of greater facility in the distribution of messages over widely extended 10 areas with increased speed and higher efficiency. The invention also relates to high speed radio signaling regardless of the distance of the transmission.

A feature of the invention relates to the 15 transmission or re-transmission or relaying of messages by radio at high speed whereby a single radio channel has a signaling capacity equivalent to that of a plurality of land lines.

20 A further feature of the invention is a provision whereby the necessity of synchronism between a transmitter and a receiving mechanical translator is eliminated.

25 A further feature of the invention relates to the provision whereby signal storing elements perform the steps of transmission, reception and translation with a minimum amount of manipulation.

30 Still other features will appear as the following description progresses.

One way of using a radio system for 35 relaying messages between several lines, would be to provide as many radio transmission channels as there are pairs of lines to be repeated between, and to arrange each line to repeat into its own radio channel and the corresponding distant line to receive from the same channel. The channels might be 40 fixed by a succession of wave lengths used in transmitting the messages for the several lines. In such a system, the radio transmission must be simultaneous with the wire transmission, and repeating means must be 45 provided between the radio system and each line that is to cooperate with the radio system. The radio system must be complicated to provide for any considerable number of 50 radio channels, and although the use of the radio system may be confined to a few hours

of the day on account of strays, the lines 55 must all be available for cooperation with the radio system (if it is to operate at maximum efficiency) at those particular times when radio communication can be carried on satisfactorily.

Another way of relaying between several lines by radio or of sending a large number of signals in a short time, is provided by the invention and includes the provision of a radio communication channel with a high 60 speed of signal transmission. According to the present invention, messages to be transmitted or relayed through the radio system are impressed on signal storing elements and the radio transmission can be effected 65 at very high speed from these storing elements. Also the most favorable time for transmitting can be chosen irrespective of the time at which the messages are received 70 over land lines for re-transmission by radio.

75 It should be observed that a radio system is not subject to the same speed limitations that lines are. The signaling speed over a line may be limited both by the constants of the line, especially in the case of a submarine cable, or by the standardization that has been made in the actual signaling sets.

80 Thus, the best signaling speed of a trans-Atlantic cable is of the order of 300 letters a minute and a high speed for short cables is 85 700 letters a minute. In the case of a standard four-channel printing telegraph line, a high average speed is 800 letters a minute in each direction. In a radio system, however, the speed of signal transmission is 90 limited mostly by the sets themselves and to an extent by the antennæ, particularly by the sending set and sending antenna. An antenna capable of efficiently transmitting a speech-modulated wave should permit of signaling at the rate of 3000 to 5000 letters a 95 minute. According to the invention, terminal signaling means are provided to be operated at or near these speeds so that the radio system has a signaling speed equivalent to that of several lines.

100 According to the present invention, the high speed radio signaling is effected by signal storing elements and the receiving signal storing elements may be used to control re-transmission of the signals or may 105 actuate a recorder or the stored signal may be read by ear at any desired speed.

In the drawings, Figs. 1 and 2 relate to the preparation of the transmission-controlling means; Figs. 3 and 4 show methods of using the controlling means for transmitting; Figs. 5 and 6 indicate the manner of receiving the radio signals; Figs. 7 and 8 illustrate the translation of the received signals and Fig. 9 is a diagrammatical outlay of a system of distribution according to the invention.

In Fig. 9, the circles may represent the points at which a step occurs in the transmission of signals and the squares may represent the corresponding points in the reception of the messages. The points 1, 2, 3, and 4 may be widely separated from one another and from the radio station S with which they are connected by the land lines shown. Points 2 and 3 may both transmit to and receive from station S, and points 1 and 4 are shown provided with lines for one-way transmission only with the radio station S. The land lines may be telephone or telegraph lines of any type and there may be both kinds of lines present between station S and any one of the points. One of the lines for each of the separated points may conveniently be a printing telegraph line using any suitable printer code. Messages transmitted from points 1, 2 or 3 to station S are received at point 5 where they are arranged for re-transmission by the radio system indicated. If they are received telephonically, they are impressed upon a transmitting tape or other storage means at point 6 and are transmitted at high speed over the radio channel at point 7 to the distant station S'. If the message received at point 5 for re-transmission is a telegraph message, it may be received in the form of perforations in a tape or by similar means, which tape or other means is used at point 7 for re-transmission at high speed. A locally operated transmitter is also indicated at 8. The message is received at high speed at point 9 and is translated either for local reception or for perforating a tape at point 10, which tape may operate a local printer at point 11, or may be passed through a transmitter at point 12 for sending over land lines to distant receiving points 13, 14 and 15. There may also be telephonic communication between the point 12 and the points 13, 14 and 15. In a similar manner, points 14, 15 and 16 may transmit to station S' and the message may be re-transmitted by radio from points 17 at high speed to be received at high speed at point 18, and to be re-transmitted by land lines from point 19 to the distant points 2, 3, and 4. While different antennæ are indicated in Fig. 9 for sending and receiving, there might, of course, be only one antenna at each station S and S' for both sending and receiving.

In Fig. 1, the tape 25 is fed to the right through a suitable tape puncher, T. P., which perforates the tape in accordance with the signal to be transmitted in the desired code. In the figure shown, it is assumed that a code consisting of dots and dashes is to be used. Preferably a machine perforator is used of any known type operated from a keyboard or the like, the only requirement being that the perforations are reasonably accurately punched as to length and spacings. This is not so important where the message is to be translated by ear, but is a requirement where the translation is to be into printing by a machine. After the perforated tape is wound upon the reel 26, the reel is transferred to the high speed transmitter shown in Fig. 3, and the tape is unwound from the reel 26 and passed to the left between the transmitting contacts 27 and 28. When these contacts are allowed to meet due to a perforation in the tape, the grid battery 29 of the modulator M is short-circuited through resistance 30. Any suitable type of oscillator and modulator or other transmitting arrangement can be used. In the form shown, the oscillator O is in series with the modulator M. The period of the generated oscillations is controlled by the constants of the antenna 33. The variable condenser 31, serves as a power coupling adjustment of the oscillator with the antenna, and the oscillations are impressed from the output coil 32 to the antenna circuit 33 and in part to the grid control winding 34. Brush contacts 27 and 28 by short-circuiting the battery 29 through resistance 30 vary the impedance of the modulator M upon which the amplitude of the radiated wave from oscillator 9 depends. The tape 25 is run at a high speed through the transmitter and the signals are transmitted reversed and at a high speed in the form of wave trains.

This general method of impressing signals on a storage element in a forward direction and transmitting them from the storage element in a reverse direction possesses several advantages among which may be mentioned the greater facility in manipulation of the storage elements and the considerable degree of secrecy that may be obtained. For instance, signals transmitted at a readable rate by this method over a line could not be read by ear, but would require the use of a recorder.

In some cases it may be preferred to use other means than a perforated tape for transmitting, particularly when it is found difficult to run the tape at the high transmitting speed that may be desired. Fig. 2 shows a means for impressing the signals that are to be transmitted upon a telegraphone wire 35 which passes to the right through a magnetizing spool 36. The spool

36 is energized from source 37 controlled by a suitable type of transmitter which is capable of impressing the signals accurately proportioned as to length and spacings upon the wire 35. For transmitting the stored signal at high speed, the spool 38 on which the telephone wire is wound is transferred to the transmitter of Fig. 4 and the wire is unwound and passed to the left 10 through the reproducing spool 40 at high speed.

With the signals impressed upon the telephone wire 35 in the manner that is indicated in Fig. 2, by current impulses of 15 the duration of the dots and dashes, it is evident that the current induced in reproducing spool 40 will not consist of dots and dashes, but of a short impulse in one direction at the beginning of each signal 20 element, such as a dot or a dash, and a short impulse in the opposite direction at the end of each signal element. These short impulses are transmitted through the coupling 41 to the circuit containing resistance 42 and the large condenser 43. A short impulse of one sign indicating the beginning 25 of a signal element will charge the condenser 43 through resistance 42 and the charge of the condenser will continue to 30 maintain the grid of the thermionic relay 44 at the corresponding potential. The end 35 of the signal element will be denoted by a short impulse of the opposite sign which will neutralize the charge on condenser 43 and therefore bring the potential of the 40 grid back to normal. If it be assumed that the impulse at the beginning of each signal is such as to make the grid more positive so as to increase the conductivity of relay 44, an impulse will be transmitted to the 45 output circuit 45 of the relay of a duration corresponding to the length of the signal element. 46 indicates any suitable type of amplifier and 47 represents a generator and modulator which may be of the type indicated in Fig. 3 or any other suitable type.

The transmitted signals may be received at their high speed of transmission on the antenna 50 in Fig. 5. With a sufficiently 50 long wave length and a sufficiently high speed of signal transmission and of the receiving telephone wire, the usual detector or its equivalent is not necessary. For instance, if the signal transmission speed is 55 twenty times hand sending and if a receiving translating note of one thousand is desired, the wave length corresponding to a frequency of 20,000 might conveniently be used, i. e., a wave length of 15,000 meters. 60 The wave is transmitted through the usual tuned circuit 51 to the amplifier 52 and is impressed upon the telephone wire 53 by means of the magnetizing spool 54. The wire is run at high speed to the left and 65 is wound on spool 55. At the wave length

mentioned, the frequency of the note recorded on the wire is 20,000, and the signal as stored, it will be remembered, is backwards. By running the wire 53 forwards in Fig. 7 through a reproducing coil 56 at 70 reduced speed, say 1/20 of the receiving speed, an operator may read the signals in the telephone receiver 57 at a rate corresponding to hand sending. By controlling the speed of the wire through the coil 56, 75 the operator may vary the speed of the signals heard and may incidentally vary the signal note.

If the ratio of the radio frequency to the frequency of the note at which it is desired 80 to transcribe the signals, is much greater than the ratio of the speed of the high speed signaling to the signal-transcribing speed, it would probably be desirable to use a detector in the receiving circuit as is indicated 85 in Fig. 6. A local generator 80 may produce a frequency different from the frequency of the transmitted wave and the detector 81 may serve to give the difference frequency which is amplified by an amplifier 90 52 as in Fig. 5.

Fig. 8 shows a means for translating a received signal mechanically into the form of perforations in a tape, whether the received signals are from the radio system or 95 from a line. The wire 53 is drawn from reel 55 at a constant speed through the reproducing spool 57 by means of the pulley 58. This pulley is driven from motor 59 through suitable reduction gearing 60 and 100 may contain a V groove in which the telephone wire is held wrapped once around the pulley. Any other means may be employed which will drive the wire at a constant speed. The motor 59 which is preferably an induction motor may conveniently be fed from local power mains 61 which will generally insure sufficient constancy of speed. Driven from motor 59 are also an oscillating punch 62, and a feed roller 63 the 110 latter being connected through suitable gearing 64. Roller 63 draws the tape 65 at a constant speed from the reel 66 along beneath the reciprocating punch 62. The tape itself is sufficiently yielding beneath the 115 punch to be normally unaffected by the striking of the punch. On the under side of the tape 65, (which is shown broken away beneath the punch) is a movable punch seat 67 having a hole which is directly in line 120 with the punch 62. When, and as long as, the seat 67 is held up against the under side of the moving tape, the vibrating punch 62 perforates the tape and the perforating action ceases when the seat 67 is allowed 125 to move to its normal position. The position of the seat 67 is controlled by the magnet 68 which is energized for different lengths of time in accordance with the dots and dashes that are recorded on the tele- 130

raphone wire 53. The circuits for controlling magnet 68 contain the spool 57, the amplifier set 69 and the detector 70. The frequency which it is desired to detect is prevented from being shunted by the plate battery supply circuit of the amplifier 69 by means of the practically infinite impedance offered to currents of this frequency by the anti-resonant circuit 71. By the well-known action of the detector 70, the current which actuates magnet 68 will be practically continuous current of duration corresponding to the length of the respective wave-trains recorded on the wire 53, and magnet 68 will therefore remain energized for periods corresponding to dots and dashes. Since the wire 53 and the tape 65 are driven from the same motor their speeds bear a constant relation to each other and except for errors in the actuation of the translating means, the signals will be recorded on the tape 65 with the same regularity with which they are stored on the wire 53. From the perforator, the tape may pass into a re-transmitter of any suitable type for re-transmission or the tape may pass into a printer diagrammatically indicated at 72 which is adapted to transcribe the message directly into print.

This printer may be of the type disclosed in my United States Patent 1,456,503, dated May 29, 1923.

In case the message stored in the wire 53 is to be re-transmitted over land lines for instance, the switch 73 may be thrown to the right to include the telegraphic relay 74 in the circuit of the detector 70. As the wire 53 is passed through the spool 57, the signals recorded on the wire actuate relay 74 which repeats the signals over the line 75 when the switch 75' is opened.

The tape perforator may be controlled otherwise than by the telephonic wire 53. It may be desirable for instance to prepare a tape 25 (Fig. 1) for high speed transmission in accordance with signals received over a land line as indicated at 76, Fig. 8. By throwing the switch 77 to its lower position, the magnet 68 is included in the circuit controlled by the relay 78 and with the motor 59 operating to move the tape beneath the punch 62 at the desired rate, the tape may be perforated by the signals received over the line 76.

It is not necessary to use the Morse continental code, and it may be desirable to use other codes if the messages are to be transcribed into print. However, an advantage of the continental code is that if the strays are so bad as to produce as strong effects in the receiving telephonic wire 53 as are produced by the signals, in which case a mechanical translator would very likely be unable to pick out the signal, the message may be read by ear by a skilled operator

who is able to distinguish the signal note. A special printer code could not easily be read by ear.

It should be noted that no synchronism in the usual sense of the word is necessary between sending and receiving apparatus according to this invention. The only requirement is approximate constancy of speed for the moving tapes or other storing elements in each of the steps of tape punching, transmitting, receiving and in transcribing, if this is done by a machine, although the speed employed in each of the steps enumerated may not be the same. The necessity of constant speed in the tape punching step is that the dots, dashes and spaces may be accurately made, if the message is to be transcribed into print. If the same motor 59 drives both the telephonic wire and the recording tape as in Fig. 8, the speed relation in the transcribing step is taken care of. The actual speed of the receiving telephonic wire in Figs. 5 and 6 may be only a fraction of the speed of the transmitting tape and each may be controlled entirely independently of the other, there being no necessity for their being in step or in phase, but simply that their speed be kept substantially constant.

Several of the features of the invention that have been described as elements in a radio transmission system are applicable also to line transmission, and they are not to be understood as limited, therefore, to use in a radio system.

The particular circuit arrangements that have been used to illustrate the invention, it is to be understood, are not to be construed as limiting the invention, nor are the numerical values which have been given throughout the specification to be considered as in any way restricting the invention, the scope of which is defined by the appended claims.

What is claimed is:

1. In the art of signaling the method which comprises impressing signals on a storage element in a forward direction, transmitting said signals from said storage element in a reverse direction, receiving the transmitted signals on a storage element in said reverse direction, and translating said signals from said last-mentioned storage element in a forward direction, into electrical impulses.

2. In the art of signaling, the method which comprises impressing signals on a storage element moving in a forward direction at low speed, moving said element in a reverse direction at high speed to transmit said signals, receiving said signals on a storage element moving in a reverse direction at high speed, and translating said signals from said last-mentioned storage element moving in a forward direction at low speed, into electrical impulses.

3. In the art of signaling, the method which comprises receiving signals on a storage element from a telegraph line at the normal telegraph transmission speed of said line, retransmitting said signals from said storage element at high speed several times said normal speed, receiving said signals on another storage element at said high speed, and retransmitting said signals from said 10 other storage element at said normal speed.
4. The method of repeating signals between each of a plurality of transmission lines having a normal transmission rate and a corresponding one of a plurality of other 15 distant transmission lines having similar transmission rates, which comprises receiving signals from each of said plurality of lines at the line transmission rate on a separate storage element, retransmitting said signals from said storage elements at a speed a number of times greater than said line transmission rate in the form of radiated waves to a distant station, receiving said signals at the distant station on corresponding storage elements, and retransmitting said signals from said last-mentioned storage elements separately over the corresponding distant transmission lines at their 25 respective line transmission rates.
5. The method of repeating signals between two separate line sections which comprises receiving said signals from the first line section on a storage element, retransmitting the said signals from said storage element in a reverse order by radio transmission, receiving said signals in reverse order on a second storage element, and retransmitting said signals in their original order over the second line section.
6. In a signaling system, a line, means for transmitting signals over said line at a line transmission rate, a radio communication channel, means for repeating said signals over said radio channel through the medium of a signal storage element and at a transmission rate a number of times greater than said line rate, another line, and means for retransmitting said signals from said radio channel to said other line at said line rate through the medium of another signal storage element.
7. A communication net comprising a transmission line system and another transmission line system at a distance, a radio system having stations at each of which one of said transmission line systems terminates, means at a radio station for receiving signals from each of the lines of one of said transmission line systems at the line transmission rate, and for retransmitting said signals through the radio system at a rate several times said line transmission rate and means for receiving said signals at the other of said radio stations and for retransmitting said signals over the lines of the 40 other transmission line system at a line transmission rate.
8. In a signaling system, two separated lines and a repeating circuit between said lines comprising a radio system arranged to retransmit over the second line the signals received from the first line, said repeating circuit including means for transmitting said signals through the radio system at a rate several times the rate at which signals are sent over either line.
9. In a signaling system, a plurality of transmission lines, means for transmitting signals simultaneously over the lines at a given transmission rate, and means for receiving said signals including signal storing elements for the respective lines, a radio signaling system, means controlled by said storing elements for transmitting said signals from the several lines in succession over said radio signaling system at a rate several times said given rate, means including signal storing elements for separately receiving the signals from the respective lines at said high rate, other transmission lines, and signal transmitting means for each of said other transmission lines controlled by a respective one of said second-mentioned storing elements.
10. A radio signaling system, a wire signaling system having a normal signaling rate, means for transmitting signals through said radio signaling system at several times said rate, means including a signal storing element for receiving said signals and for retransmitting said signals over said wire signaling system at said normal rate.
11. Means for mechanically translating electromagnetic signal waves comprising a magnetic strip, means for rapidly moving said strip and subjecting it to the influence of said waves for receiving magnetic impressions in accordance with said signal waves, and a tape punching mechanism controlled by said strip for perforating a tape in accordance with the signals impressed on said strip.
12. A translator for signals transmitted by high frequency electromagnetic waves comprising a storage element for receiving and recording said high frequency waves, a tape and a tape punching mechanism, and means controlled by said storage element for actuating said tape punching mechanism to perforate said tape in accordance with said signals.
13. A translator for signals transmitted by electromagnetic waves comprising a storage element, means for subjecting said element to the influence of said waves for receiving impressions in accordance with said waves while moving at a high speed, means for moving said storage element at a low speed and for translating the stored impressions into electrical currents of an audio 125

frequency, a detector circuit for translating said currents of audio frequency into sustained currents corresponding to said signals, and an electromagnet operated by said 5 currents.

14. A signal-translating arrangement comprising a storage element sensitive to electromagnetic waves, high-frequency wave receiving circuits for impressing and recording received waves on said storage element, a circuit including a detector for translating said recorded waves into current impulses corresponding to received signals, and a recording device actuated by said impulses to 10 record said signals.

15. An arrangement for translating signals received by electromagnetic waves, into perforations of a tape, comprising a strip or wire of magnetizable material, means for 15 impressing variations corresponding to the received electromagnetic waves on said strip or wire, driving mechanism for driving the strip or wire and said tape at corresponding rates, punching mechanism for said tape, 20 and a circuit including a detector for producing current impulses from the variations on said strip for actuating said punching mechanism.

16. A translator for signals comprising 30 a storage element on which said signals are stored, a tape to be punched in accordance with the stored signals, a continuously reciprocating punch for said tape normally ineffective, a magnet for making said punch 35 effective to punch said tape, means for moving said tape beneath said punch, and a circuit for translating said stored signals into electrical currents for actuating said magnet to control the punching of said 40 tape.

17. A signal recorder comprising a tape to be perforated in accordance with received signals, a continuously actuated punch normally ineffective in punching said 45 tape, a magnet for rendering said punch effective to perforate said tape, means for moving said tape beneath said punch, and a circuit for operating said magnet in accordance with said signals to control the 50 punching of said tape.

18. In a signaling system, means for receiving signal waves, a telephone wire for recording the received signals in the form of magnetic variations in said wire, a 55 tape and a common driving means for driving said wire and said tape, a perforating mechanism comprising a continuously moving cutting member, and a magnet for rendering said member operative to perforate 60 said tape, means for translating said magnetic variations into electrical impulses, and a circuit for controlling said magnet in accordance with said impulses.

19. A transmission line, a radio signaling 65 system, a second transmission line, said

radio system having a signaling rate several times as high as that of said transmission lines, receiving means including signal storing means for receiving signals over the first said transmission line at the line-signaling rate, radio transmitting means controlled by said receiving means for transmitting said signals through said radio system at the high radio-signaling rate, radio receiving means including signal storing 70 means for receiving said signals from said radio system, and transmitting means controlled by said radio receiving means for transmitting said signals over said second transmission line at the line-signaling rate. 75

14. In a radio signaling system, signal receiving means including a signal storing element for receiving radio signals at high speed, and means for translating said signals at low speed into printed characters. 80

21. In a radio signaling system, signal receiving means including a signal storing element for receiving radio signals at a high speed, and means controlled by said storage element for punching a tape in accordance 90 with said signals.

22. The method of repeating telegraphic signals from a high-speed transmission channel to a low-speed transmission channel comprising impressing the high-speed received signals on a storage element sensitive to electromagnetic variations, thereafter utilizing said storage element to transfer said signals mechanically to a second storage element adapted to receive mechanical impressions and retransmitting said signals from said second storage element at low speed over said low-speed transmission channel. 100

23. The method of translating electromagnetic wave trains into direct current impulses comprising recording said wave trains at variations on a magnetically susceptible element, producing current variations from the recorded variations, and 110 rectifying said currents. 105

24. The method of translating short and rapidly-recurring wave trains into longer and less rapidly recurring direct current impulses comprising recording said wave 115 trains as variations along a magnetically susceptible element, utilizing said variations to reproduce current variations at lower frequency than the frequency of the received waves, and rectifying said current variations to produce direct current impulses. 120

25. The method of receiving high speed radio transmissions comprising subjecting a magnetic strip to the influence of the high-frequency waves while said strip is moving at a high speed to record received signals on said strip, translating the recorded signals into current of low frequency while said strip is moving at a slow speed, and converting 125 130

said current into impulses suitable for actuating an electromagnetic recorder.

26. Receiving and recording arrangements for a radio signaling system comprising a wave-receiving circuit, a magnetic strip and means to subject different portions of said strip in rapid order to the influence of the received waves to record received signals on said strip, means for thereafter translating the recorded signals into currents of low frequency including means for presenting the said portions of said strip in a slow order to said translating means, an amplifying and detecting circuit for converting said translated currents into

signal impulses of current, and an electromagnetic receiver actuated by said impulses.

27. In a radio receiving system, a magnetic strip for recording received electromagnetic wave signals as magnetic variations along said strip, a detector for converting said magnetic variations into current impulses, a tape and a tape-punching mechanism controlled by said impulses for punching said tape in accordance with the received signals. 20 25

In witness whereof I hereunto subscribe my name this 22nd day of September, A. D., 1919.

RAYMOND A. HEISING.
